UNITED STATES PATENT OFFICE

136,895

DESIGN FOR A COMBINED BILLFOLD AND COIN PURSE

Nels H. Swanson, Chicago, Ill.

Application October 16, 1943, Serial No. 111,401

Term of patent 7 years

To all whom it may concern:

Be it known that I, Nels H. Swanson, a citizen of the United States, residing in the city of Chicago, county of Cook, and State of Illinois, have invented a new, original, and ornamental Design for a Combined Billfold and Coin Purse, of which the following is a specification, reference being had to the accompanying drawing, forming a part thereof.

In the drawing:

Fig. 1 is a perspective view of a combined bill-

fold and coin purse embodying my new design.

Fig. 2 is a rear elevational view of the same.

Fig. 3 is a perspective view showing the purse in open position.

Fig. 4 is a left end elevational view.

Fig. 5 is a right end elevational view.

Fig. 6 is a bottom plan view.

I claim:

The ornamental design for a combined billfold and coin purse, substantially as shown.

NELS H. SWANSON.
